COMBINED SPOON AND BOTTLE CLOSURE

Filed Nov. 22, 1927

INVENTOR

Ferdinand Phillipson.

BY

Louis L. Amand

ATTORNEY

UNITED STATES PATENT OFFICE.

FERDINAND PHILLIPSON, OF NEW YORK, N. Y.

COMBINED SPOON AND BOTTLE CLOSURE.

Application filed November 22, 1927. Serial No. 234,946.

This invention relates to means whereby devices such as spoons may be attached to medicine bottles or the like, and relates more particularly to combined bottles caps and spoon.

5 Frequently it is necessary to take liquid medicine when away from home or where one does not have available a teaspoon with which the measurement of medicine is ordinarily made. Furthermore, it is extremely inconvenient and really impracticable to carry an ordinary spoon around to meet such emergencies.

An important object of the invention is to provide devices which obviate such difficulties 15 and meet all reasonable requirements, and which are simple and economical to manufacture. Another object of the invention is to provide a bottle closure member with a spoon-bowl attached directly thereto without the intervention of a stem or handle portion. Another object of the invention is to provide a spoon or other measuring device integral with a metal bottle cap or closure member, and so made as to lie along the neck of a bottle to 25 which the cap is applied, without projecting beyond the outlines of the main body of the bottle. Obviously, the invention may be applied to particular advantage to bottle caps of the type adapted to be secured to bottles by 30 giving them a part turn after placing them in position.

Other features and advantages will appear upon consideration of the following description and of the accompanying drawings in 35 which:

Fig. 1 is a fragmentary view showing the upper part of a bottle having one embodiment of the invention applied thereto;

Fig. 2 is a side elevation, partly in section, 40 of the structure shown in Fig. 1;

Fig. 3 is a view similar to Fig. 1, but illustrating another form of the invention; and

Fig. 4 is a view, partly in section, illustrating another form of the invention.

45 Referring to the drawings in which similar numerals refer to similar parts throughout the several views 10 indicates a bottle (Fig. 1) with a neck 11 having suitable provisions, such as projections 12, to be engaged by suitable lugs or projections at the interior 50 of a cap 13, such as inwardly projecting flanges 14 (Fig. 2) at the lower edge of the cap. The projections 12 are here shown as having inclined lower surfaces but it is com-

mon practice to obtain the wedging action by 55 inclined surfaces on the flanges or inwardly projecting parts 14.

According to the approved embodiment of the invention illustrated in Figs. 1 and 2 the cap 13 is formed with a spoon or spoon-bowl 60 15 and of substantially standard capacity integral therewith. Preferably, as here shown, there is no handle to the spoon which is connected directly with the cap by the relatively thin metal and may readily be bent back from 65 the cap to render its use more convenient. The cap or closure 13 may be used with or without a cork in the mouth of the bottle, such caps ordinarily being formed with linings of suitable material such as cork to assure a 70 liquid-tight seal.

In the event that there is insufficient room for the bowl of the spoon to be placed lengthwise of the neck of the bottle, the cap 13 may be provided with an integral extension in 75 the form of a spoon 15^a connected at the middle of one side with the cap (Fig. 3).

Under certain conditions, particularly where the bottle has a short neck and the body of the bottle extends a substantial distance to the side, the cap 13 may be provided with a deep-bowl spoon or cup 15^b (Fig. 4).

It will be evident that the spoons, cups or measures attached to the bottle caps or closures may be applied to bottles without interfering with the packaging of the bottles and that, in the event one purchases a bottle of medicine provided with such a combined closure and spoon, he will have at hand a suitable substitute for the ordinary spoon which 90 he would ordinarily need and would probably have considerable difficulty in getting unless he happened to be at home. The present invention obviates any difficulty of this kind.

The device of the present invention may 95 readily be stamped from sheet metal such as is ordinarily used in making bottle caps and the spoon bowl or measuring receptacle may be made of any available size. Ordinarily, however, a measure with the capacity of one 100 teaspoonful meets all requirements.

The foregoing detailed description has been given for clearness of understanding and no undue limitation should be deduced therefrom, but the appended claims should be 105 construed as broadly as possible, in view of the prior art.

Having thus described my invention, what

I claim as new and desire to secure by Letters Patent of the United States is:

1. In combination, a sheet metal bottle closure, and a measuring receptacle attached integrally at one edge directly to said bottle closure and adapted to lie outside of and along the neck of the bottle and between the mouth and the body of the bottle.
2. In combination, a bottle closure including a thin metal shell, and a spoon-bowl integral therewith with one edge of the bowl and one edge of the shell substantially coincident so that the bowl may assume a position at the side of the neck of a bottle when the shell is in effective position but may be shifted with reference to the shell by bending the sheet metal at the line of division therebetween.
3. In combination, a bottle closure including a sheet metal part to be secured on the centrally disposed neck of a bottle at its mouth, and a spoon-bowl integral therewith at one edge of the bowl and one edge of said

part and so arranged as to lie along the neck at the outside thereof and between the mouth 25 of the bottle and the base of the neck.

4. A unitary combined bottle cap and tea-spoon stamped from sheet metal and with the bowl having its edge at one part thereof substantially coincident with the edge of the cap so that by bending the sheet metal at the line of division between the cap and the tea-spoon, the spoon may without distortion thereof be brought to a convenient position for use, with reference to the cap. 30

5. A unitary sheet metal device including a bottle cap and a spoon bowl with its edge substantially at the edge of said cap so that by bending the sheet metal at the line of division between the cap and the spoon bowl, the 40 bowl and the cap may without distortion of either, be brought into the proper relation for convenient use of the spoon.

In witness whereof, I affix my signature.

FERDINAND PHILLIPSON.
